(57) **CLAIM**

The ornamental design for a recessed lighting fixture, as shown and described.

DESCRIPTION

This application contains subject matter which is related to the subject matter of concurrently filed U.S. Design patent application Ser. No. 29/612,021, entitled "Lighting Fixture" by Mark A. Gaynor; U.S. Design patent application Ser. No. 29/612,024, entitled "Lighting Fixture Having An Illumination Effect" by Mark A. Gaynor; which applications are hereby incorporated in their entirety herein by reference.

FIG. 1 is a right perspective view of a recessed lighting fixture according to a first embodiment of the new design;

FIG. 2 is a left perspective view thereof;

FIG. 3 is a front elevational view thereof;

FIG. 4 is a right side elevational view thereof;

FIG. 5 is a left side elevational view thereof;

FIG. 6 is a top view thereof;

FIG. 7 is a bottom view thereof;

FIG. 8 is an enlarged view of detail 8 of FIG. 1;

FIG. 9 is an enlarged view of detail 9 of FIG. 2;

FIG. 10 is an enlarged cross-sectional view taken along line 10-10 of FIG. 3;

FIG. 11 is a front elevational view thereof, but shown illuminated;

FIG. 12 is a cross-sectional view taken along line 12-12 in FIG. 11;

FIG. 13 is a front elevational view of a second embodiment of the recessed lighting fixture according to the new design, the sole difference between this embodiment and the first embodiment is the symbolic break lines shown in the figure;

FIG. 14 is a right perspective view of a third embodiment of the recessed lighting fixture according to the new design with stipple shading indicating a contrasting appearance;

FIG. 15 is a left perspective view thereof;

FIG. 16 is a front elevational view thereof;

FIG. 17 is a right side elevational view thereof;

FIG. 18 is a left side elevational view thereof;

(Continued)

FIG. 19 is a top view thereof;
 FIG. 20 is a bottom view thereof;
 FIG. 21 is an enlarged view of detail 21 of FIG. 14;
 FIG. 22 is an enlarged view of detail 22 of FIG. 15;
 FIG. 23 is an enlarged cross-sectional view taken along line 23-23 of FIG. 16;
 FIG. 24 is a front elevational view thereof, but shown illuminated;
 FIG. 25 is a cross-sectional view taken along line 25-25 in FIG. 24; and,
 FIG. 26 is a front elevational view of a fourth embodiment of the recessed lighting fixture according to the new design, the sole difference between this embodiment and the third embodiment is the symbolic break lines shown in the figure. The cross-section of the recessed lighting fixture in FIG. 10 corresponds to cross-sections along the length of the opening in the recessed lighting fixture shown in FIG. 3. The cross-section of the recessed lighting fixture in FIG. 23 corresponds to cross-sections along the length of the opening in the recessed lighting fixture shown in FIG. 16. FIGS. 13 and 26 are shown with symbolic break lines through the recessed lighting fixture, the appearance of any portion of the article between the break lines forms no part of the claimed design. The stippling shown in FIGS. 11 and 24 is solely for the purpose of illustrating the appearance of illumination and does not represent texture or surface ornamentation. The broken lines in the drawing disclosure illustrate portions of the environment and the recessed lighting fixture and form no part of the claimed design.
